TUNING INDICATOR SYSTEM

Kenneth A. Chittick, Haddonfield, N. J., assignor
to Radio Corporation of America, a corpora-
tion of Delaware

Application June 30, 1936, Serial No. 88,176

6 Claims. (Cl. 250—20)

The present invention relates to multi-wave band receivers and, more particularly, to tuning or resonance indicator systems therefor. The present invention has for its object to provide an improved tuning or resonance indicator system wherein a uniform tuning response or resonance indication over a relatively wide tuning range including a plurality of wave bands, may be derived.

10 Heretofore, in providing tuning indications in response to received carrier waves or signals in a multi-wave band receiver, a differing degree of response has been obtained in one wave band as compared with that in another, because of inherent circuit connections tending to make the tuning indications weaker on the higher frequency or shorter wave bands. It is, therefore, an object of the present invention to provide means having a uniform tuning response as a tuning indicator, whereby this operating characteristic may be overcome.

15 It is a further object of the present invention, to provide a tuning indication system of the above character wherein a tuning indicator tube of the electronic, grid-controlled type known commercially as the "Magic eye", which is provided by the commercially available RCA 6E5 tube, may be used.

20 As is known, the deflection on the indicating screen of a tuning indicator tube of the above type, is proportional to the voltage impressed upon the control grid of the amplifier portion of the tube.

25 It is also known that the deflection or tuning indication as normally provided in commercial radio receivers now on the market is relatively broad. This renders the tuning operation more difficult on certain weaker signals as received from more distant broadcasting stations.

30 Accordingly, it is a further object of the present invention to provide an improved tuning indicator system in which the response of the indicator tube is substantially the same for all signals received, regardless of the strength of the carrier wave and with a high degree of selectivity, whereby the indication is produced only when the receiver is tuned correctly to the desired carrier wave or signal.

35 In carrying out the objects of the invention, a tuning indicator tube circuit is provided in connection with a separate intermediate frequency amplifier channel which controls the deflection of the indicating portion of the tube, the intermediate frequency amplifier further including a sharply tuned coupling transformer.

With this circuit, the indicator tube will not begin to deflect until within approximately five kilocycles of the center of the carrier. The maximum deflection is very sharp and occurs only on the exact center of the carrier wave. The broadness of the "Magic eye" tuning is thus eliminated, and the operator of the receiver is enabled to tune the same to exact resonance.

40 A further object of the present invention is to provide a tuning indicator system in which the sensitivity of the indicator device may be adjusted for conditions which obtain in any given locality in which the receiver is used, and for loss of sensitivity because of aging of the tubes and circuit elements. It will be appreciated that this feature is desirable, since the receiver may be operated in some cases in a metropolitan district and in the vicinity of a broadcasting station, and in other cases in remote portions of the country, at extreme distances from broadcasting stations, and for compensating for aging of the circuit elements and for differences in location, a sensitivity adjustment of the tuning indicator tube is desirable.

45 The invention will be better understood from the following description, when considered in connection with the accompanying drawing, and its scope will be pointed out in the appended claims.

50 In the drawing, Fig. 1 is a schematic circuit diagram of a portion of a superheterodyne receiver embodying the invention; and

55 Fig. 2 is a schematic circuit diagram showing a modification of a portion of the circuit of Fig. 1.

60 Referring to the drawing, an intermediate frequency amplifier tube is indicated at 5, and is coupled with an intermediate frequency coupling transformer 6 to receive amplified signals from preceding usual tuning and frequency changing portions of the receiver. This portion of the receiver is not shown, for the reason that such receivers are well known and understood, and the omission of the input end thereof serves to simplify the drawing.

65 Intermediate frequency signals, amplified by tube 5, are applied through an output coupling transformer 7, to a second detector tube 8, which includes two diode rectifiers, in the present example, one of which is used for initial bias and the other of which is used as a detector and for automatic volume control purposes.

70 The detector diode is indicated by the anode 9 and the cathode 10, while the bias control diode is indicated by the anode 11 and the cathode 12, 50

the heater for the cathodes being indicated at 13. This tube may be of the RCA 6H6 type.

The detector diode circuit includes the tuned secondary 14 of the intermediate frequency transformer 7, which is connected between the diode anode 9 and cathode 10, through an output resistor 15-16, with the cathode end thereof connected to ground as indicated at 17.

Automatic volume control potentials are applied to an automatic volume control lead 18 from the diode circuit, through a filter comprising a series resistor 19 and a by-pass capacitor 20. The diode output resistor is also provided with a shunt by-pass capacitor 21.

15 Audio frequency signals are derived from the diode output resistor by a tap connection 22, having an audio frequency output lead 23. In the absence of signals, a biasing potential is supplied to the lead 18, to establish thereon a negative potential with respect to ground sufficient for normal biasing of the receiving tubes. This potential is derived from a series bleeder resistor 25-26-27 connected between a negative supply lead 28 and ground 29.

25 A tap point 30 on the bleeder resistor is connected through a lead 31 and a filter comprising a series resistor 32 and by-pass capacitor 33, to the cathode 12 of the bias supply diode. The anode 11 of the bias supply diode is connected 30 through a lead 34 with the bias supply lead 18.

It will be seen that the potential existing between the tap point 30 and ground 29, in connection with the bleeder resistor, is applied to the lead 18 through the ground connection 17, resistors 16, 15 and 19, and causes current to flow through the diode 11-12 and the resistor 32, by way of lead 31, to the terminal at 30. It will also be seen that the current flows through the diode output resistor 15-16, thereby providing an initial biasing potential to the lead 18. In the presence of a received carrier wave, the diode 9-10 causes current to flow through the output resistor 15-16, and as soon as the drop in potential increases above that established by the initial biasing rectifier, the received carrier wave serves to control the potential applied to the lead 18, and thereby provides automatic biasing potentials for the receiving system.

The initial biasing potential may be reduced by 50 short-circuiting one of the resistor sections, such as the section 27, by means of a switch 36 which is connected with the wave band exchange means of the receiver, as indicated by the dotted connection 37, whereby the automatic volume control 55 potential applied to the lead 18 is rendered more effective for certain wave bands than for others. For example, it has been found that for the shorter wave bands, the initial biasing potential is preferably reduced to render the receiving system 60 more sensitive and more readily responsive to changes in carrier wave strength at low amplitudes.

As the automatic volume control means is shown and described only by way of example and 65 is not per se, part of the present invention, the same is believed to require no further description.

In accordance with the invention, the tuning indicator tube, indicated at 38, is arranged to receive signal indications through a separate intermediate frequency amplifier channel from the signals applied to the second detector 8, and from a point preceding the automatic volume control. For this purpose, the indicator tube 38 is preceded in the intermediate frequency amplifier 75 channel by an intermediate frequency amplifier

stage including the tube 39 and by a rectifier stage including the device 40.

The amplifier tube 39 is of the high gain, pentode type, having a cathode 41 connected with ground 42, a control grid 43 connected through a coupling coil 44 with the lead 18, as indicated at 45, to receive a biasing potential therefrom, a screen grid 46, a suppressor grid 47, and an output anode 48. The latter is provided with an output circuit 49 in which is located the primary winding of an intermediate frequency coupling transformer 51, and, together with the screen grid, is connected to a positive source of anode potential represented by the lead 52. Suitable filter resistors and by-pass capacitors, 53 and 54, respectively, are provided in circuit therewith.

The transformer 51 may be of the iron core type and is sharply tuned to the intermediate frequency carrier wave to prevent the passage of signals in a band wider than substantially five kilocycles. The tuned secondary 55 is connected between the anode electrode 56 of the rectifier 40 and a terminal of an output potentiometer 57, the opposite end of which is connected to ground, as indicated at 58.

The cathode 59 of the rectifier 40 is likewise connected to ground 60, thereby completing a diode rectifier circuit through the primary winding 55. The latter, together with a tuning capacitor 61, provides a sharply tuned input circuit for the rectifier.

The rectifier 40 may be an RCA 6H6 tube, and the remaining diode elements therein, as indicated at 62, are connected to ground and are not used. The grounding connection serves to render them substantially ineffective in connection with the rectifier circuit.

The tuning indicator tube 38 may be of the type known as the RCA 6E5, which comprises a target electrode 65 which receives an electronic bombardment from a cathode 66 and fluoresces with a green light. The cathode is connected to ground through a lead 67 and a shield wire 68 surrounding a signal input lead 69. The input lead 69 serves to connect the control grid 70 of the tube with the diode output resistor 57 through a movable contact 71 thereon. The target 65 is connected through a lead 72 with a positive anode supply lead 52.

A filter resistor 73 and by-pass capacitor 74 are provided in connection with the lead 69, adjacent to the contact 71. The filter resistor and capacitor provide a time delay means for preventing sudden changes in potential from causing too rapid change on the grid 70. The grid 70 is associated with the cathode 66, and is further associated with an anode electrode 75 which is connected with the anode supply lead 72, through a series potential drop producing resistor 76.

A grid wire 77 extends from the anode 75 to a position between the cathode 66 and a portion of the screen or target 65, and casts an electronic shadow thereon, preventing the electrons from reaching the target as the electrode 77 becomes more negative with respect to the target.

This condition is controlled by the grid 78, which varies the anode current through the anode 75 and resistor 76, an increasing negative potential on the control grid 70, causing the anode current to be reduced and likewise the drop in potential through the resistor 76. The electrode 77 is thereby permitted to approach the potential of the target and to cause the shadow thereon to be decreased in area, indicating a change in grid potential on the control grid 70.

This is made a function of the strength of the received carrier wave by rectifying the carrier wave and applying the resulting direct current potential to the control grid 70 through the filter 5 73-74.

In accordance with the invention, as shown in the present example, the carrier wave at intermediate frequency is applied to the pick-up coil 44 by coupling with the signal channel in the 10 intermediate frequency amplifier preceding the automatic volume control means or second detector, and for this purpose the coil 44 is coupled with and forms part of the intermediate frequency coupling transformer 1, thereby receiving 15 energy from the secondary circuit comprising the winding 14. The coupling is indicated in the drawing by the line 80 connecting the two coils.

The carrier wave at intermediate frequency is amplified in the amplifier stage 39 and the amplified intermediate frequency carrier wave at the resonance frequency of the sharply tuned coupling transformer 51 is then applied to the rectifier 56-59. The direct current component of the rectified carrier wave is applied to the rectifier 25 output resistor 57 to provide a biasing potential for the grid 70 of the indicator tube. Since the cathode of the indicator tube is connected to ground, and therefore to the positive end of the resistor 57, the negative potential applied to the 30 grid 70, with respect to the cathode 66, is determined by the position of the movable tap 71.

In any given locality, depending upon the average strength of received signals, or dependent upon the sensitivity of the receiver resulting from 35 aging of the tubes, the contact 71 may be adjusted to provide a sufficient negative potential on the grid 70 in the presence of a received carrier wave to just "close the eye" or provide a desired minimum shadow on the fluorescent target, for accurate tuning.

The device 71, therefore, provides means for adjusting the sensitivity of the electronic, grid-controlled indicator tube, while the sharply tuned intermediate frequency amplifier not only provides a strong, amplified signal for indicator purposes but provides this signal in a separate, sharply tuned channel which admits signals in a band of a predetermined width more narrow than that of the main signal channel for the second detector, resulting in a tuning indication at exact resonance.

Furthermore, by selecting the intermediate frequency energy or voltage from a point on the signal channel preceding the automatic volume 55 control diode or rectifier device, which is also the second detector in the present example, the tuning indication remains substantially "flat" regardless of the strength of the received carrier wave.

60 However, since the control grid 43 of the indicator amplifier is connected with the automatic volume control circuit 18, exceptionally strong signals serve to control the gain of the amplifier in the same manner as the signal amplifier.

65 An advantage in this connection lies in the fact that the change in response effected by wave band change for the automatic volume control means is at the same time provided in the separate channel amplifier for the indicator tube, 70 since the control grid 43 is under control of the automatic volume control means and operation of the sensitivity control switch 36.

In a receiver having X, A, B, C, and D bands, for receiving weather reports, standard broadcasts, police, short-wave, and ultra short-wave 75

signals, respectively, the switch 36 may be opened on bands X and A and closed on bands B, C, and D, to provide a greater sensitivity for the latter bands, thereby compensating for the lower carrier wave strength available in the reception of 5 higher frequency signals. With this arrangement, the tuning indicator tube is substantially uniformly responsive, providing a sharp tuning indication for all wave bands.

In certain receivers the sensitivity of the indicator tube may be adjusted by providing a tap connection similar to the tap 71 in connection with the wave band switch connection 37 as shown in Fig. 2 wherein the same parts and circuits have the same reference numerals as in Fig. 1.

Referring to Fig. 2, the grid lead 69 for the indicator tube is connected indirectly with the tap 71 through the time delay filter 73-74 and an additional voltage divider resistor 80.

The voltage divider resistor 80 is provided with 20 a tap 81 for the lead 69 and is connected between the tap 71 and ground whereby the voltage available across the resistor 57 between the tap 71 and ground is applied to the resistor 80. A portion of this voltage is then available at the tap 25 81 serving to reduce the voltage on the indicator tube.

This reduced voltage is desirable for the normal broadcast or "A" band since the signal strength in that band is high. For the weaker signals in 30 the "B" and "C" bands, for example, the voltage may be increased to compensate by opening a switch 82 in ground connection for the shunt voltage divider 80, whereby the full voltage of the tap 71 is available for the control lead 68. The 35 control of the switch 82 may be effected in any suitable manner as by the connection indicated whereby it is actuated in response to a wave band change.

I claim as my invention:

1. In a radio receiving system having a main signal channel, and a second detector and automatic volume control means connected therewith, the combination with an electronic tuning indicator device having a control grid, of a carrier wave rectifier device having an output resistor, means providing a variable tap connection for the control grid of the indicator device on said output resistor whereby a predetermined control potential may be applied to the indicator device, a 45 tuned amplifier connected between said rectifier device and the main signal channel preceding the automatic volume control means and detector, said amplifier being more sharply responsive to signals than the main signal channel, and means 50 for applying automatic volume control potentials to said amplifier.

2. In a multi-wave band radio receiving system having a main signal channel, and a second detector and automatic volume control means connected therewith, the combination with an electronic tuning indicator device having a control grid, of a carrier wave rectifier device having an output resistor, means providing a variable tap connection for the control grid of the indicator device on said output resistor whereby a predetermined control potential may be applied to the indicator device, a tuned amplifier connected between said rectifier device and the main signal channel, said amplifier being more sharply responsive to signals than the main signal channel, and means responsive to change in the frequency response range of the receiving system for effectively changing the control grid connection with 65 said output resistor.

3. In a multi-wave band radio receiver, the combination with an intermediate frequency amplifier, of automatic volume control means responsive to received signals conveyed through said intermediate frequency amplifier, a tuning indicator device of the electronic grid-controlled type connected with said intermediate frequency amplifier to receive signals therefrom at a point preceding said automatic volume control means, 5 said connection including a high gain intermediate frequency amplifier, a rectifier device, and a sharply tuned iron core coupling transformer between said amplifier and said rectifier device, means for deriving a biasing potential from said rectifier device for said tuning indicator device, and means for adjusting the value of said potential in response to wave band change.
- 10 4. In a multi-wave band radio receiving system having automatic volume control means, the combination with a tuned signal channel connected with said automatic volume control means to apply signals thereto, of resonance indicator means comprising a sharply tuned signal amplifier connected with said signal channel preceding 15 said automatic volume control connection, a diode rectifier connected with said sharply tuned signal amplifier to rectify signals therefrom, a diode output resistor in circuit therewith, a resonance indicator tube having a control grid variably connected with said resistor to receive an adjustable biasing potential therefrom in response to received signals, and means for adjusting said potential to compensate for changes in sensitivity resulting from changes in wave band range of said 20 receiving system.
- 25 5. In a multi-wave band receiver, the combination with automatic volume control means adjustable in sensitivity with wave band change, of an intermediate frequency amplifier stage coupled

to the signal channel of said receiver preceding said automatic volume control means and being controlled thereby, a signal rectifier device, sharply tuned coupling means connected between said rectifier device and said amplifier stage to apply signals to said rectifier device in a frequency band relatively narrow with respect to the frequency response band of the signal channel of the receiver, a tuning indicator tube having a control grid coupled to said rectifier device to receive a portion of the direct current potential therefrom resulting from signal rectification, and means for varying said last named coupling to control the sensitivity of said tuning indicator device in response to wave band change. 10 15

6. In a multi-wave band receiver, the combination with automatic volume control means adjustable in sensitivity with wave band change, of an intermediate frequency amplifier stage coupled to the signal channel of said receiver preceding said automatic volume control means and being controlled thereby, a signal rectifier device, sharply tuned coupling means connected between said rectifier device and said amplifier stage to apply signals to said rectifier device in a frequency band relatively narrow with respect to the frequency response band of the signal channel of the receiver, a tuning indicator tube having a control grid coupled to said rectifier device to receive a portion of the direct current potential therefrom resulting from signal rectification, a potential divider device in said connection, and means for opening a connection with said device thereby to vary said potential on said tuning indicator device, said last named means being operative in response to predetermined wave band change in said receiver. 20 25 30 35

KENNETH A. CHITTICK.
